UNITED STATES PATENT OFFICE.

JAMES J. BRAINARD, OF PITTSBURGH, PENNSYLVANIA, ASSIGNOR TO WESTMORELAND SPECIALTY COMPANY, OF GRAPEVILLE, PENNSYLVANIA, A CORPORATION OF PENNSYLVANIA.

DESIGN FOR A VITREOUS TOY TRAIN.

Application filed April 12, 1923. Serial No. 5,790. Term of patent 3½ years.

To all whom it may concern:

Be it known that I, JAMES J. BRAINARD, a citizen of the United States, residing at Pittsburgh, in the county of Allegheny and State of Pennsylvania, have invented a new, original, and ornamental Design for a Vitreous Toy Train, of which the following is a specification, reference being had to the accompanying drawings, forming part thereof.

In the drawings:

Fig. 1 is a view in elevation of a vitreous toy train illustrating my design.

Fig. 2 is a plan view thereof for the description of the figures of the drawings as of record.

I claim:

The ornamental design for a vitreous toy train made of glass, as shown.

JAMES J. BRAINARD.
